PRINTING MACHINE

Maurice B. Willis, Haddonfield, N. J., assignor of
one-half to Charles C. Morrison, Philadelphia,
Pa.

Application May 20, 1941, Serial No. 394,274

14 Claims. (Cl. 101—194)

This invention relates to printing machines; and has for its chief aim to enable making of graphs, charts and the like through application to printed form sheets of impressions such as symbols, solid or broken bars, and/or lines either in single or contrasting colors to indicate by differences in their length, size or location, correspondingly different values or percentages by aid of which the extents or volumes of various things may be readily and quickly ascertained and compared without the necessity for computation.

The foregoing desideratum I realize in practice, as hereinafter more fully disclosed, through provision of a printing machine of simple and compact construction in which a plurality of laterally-spaced printing bars are secured in a holder with capacity for endwise adjustment in the direction of their lengths to project forwardly to different extents from said holder; in which the holder is sustained for movement in the direction of the bars by a carrier so that the projecting ends of said bars may be brought into a position over a form sheet supported on a platen; in which the carrier is mounted for movement in a direction perpendicular to the platen so that the printing bars may be brought into contact with the sheet; in which there is a supply means for a breaker strip adapted to transversely overlie a corresponding area of the platen to prevent contact of the printing bars with such area as the impressions are being made; and in which there is an auxiliary pressure means by which the projecting ends of the printing bars may be pressed into firmer contact with the form sheet on the platen after the actuation of the carrier as aforesaid. In the machine there is also a means for applying contrastingly colored inks to different groups of the printing bars during movement of the holder as the latter is moved toward and away from the platen; and means whereby the sheet may be shifted on the platen laterally of the printing bars to predetermine the application of contrastingly colored imprints to different portions of said sheet.

Other objects and attendant advantages will appear from the following detailed description of the attached drawings, wherein:

Fig. 1 shows the top plan view of the printing machine embodying my invention, with a portion broken out to better illustrate important underlying details.

Fig. 2 is an elevation of the machine as it appears when viewed from the right of Fig. 1 like-

wise with a portion broken out to expose important structural details.

Fig. 3 is a longitudinal section of the machine taken as indicated by the angled arrows III—III in Fig. 1.

Fig. 4 is a fragmentary view in transverse section drawn to a larger scale and taken as indicated by the angled arrows IV—IV in Figs. 1 and 2.

10 Fig. 5 is a detail view in front elevation of the holder for the printing bars; and

Fig. 6 shows a chart such as may be produced in my improved printing machine.

As herein illustrated, my improved printing machine has a substantially rectangular hollow base 1 with a raised platform 2 at the rear whereof the top 3 is designed to serve as the platen or pressure plate for the sheet S, such for example as shown in Fig. 6, upon which imprints are to be made, and with a depressed portion 4 at the front thereof. The base 1 is moreover formed with vertical axis bosses 5 and 6 respectively at the front and rear corners, and with similar vertical axis bosses 7 at the sides somewhat to the rear of the frontal bosses 5, all said bosses being extended downwardly beyond the lower edges of the side walls of said frame for service as supporting feet. A pad 8 of rubber or the like overlying the platen 3 (Fig. 4) is held

30 in place by a textile cover sheet 9 whereof opposite edge margins are lapped downwardly over the sides of the platform 2 and clamped fast by bail-like members 10 and 11 of wire respectively pivoted at 12 and 13 (Figs. 1-3) to the front and rear walls of said platform. Supported upon upright lug projections 14 at the rear of the platform 2 and secured by bolts 15 is a gauge bar 16 which slightly overhangs the platen 3 (Figs. 2 and 3) and which has a pendant longitudinal

35 gauging rib 17 for abutment of the rear edge of the sheet S. To the right hand side wall of the platform 2 (Figs. 1 and 2) are secured a pair of spaced bearing brackets 18 for a shaft 19 carrying resilient feeding rollers 20, 21 for the sheet S. The feeding rollers 20, 21 project upwardly through suitable openings in a plate 22 supported by and fixedly secured to the brackets 18 at the top, and are operated by turning a finger knob 23 at the rear end of the shaft 19. The roller

50 20 is opposed by a short fixed supplemental plate 25 (Fig. 4) which is spaced slightly upward from the plate 22 at the corresponding end of the latter, while the roller 21 is opposed by the contiguous overhanging end of the gauge bar 16, see 55 Fig. 2.

Journalled for free rotation about a pin 26 at the upper end of a bracket arm 27 secured to the opposite side wall of the base 1 (Figs. 1 and 4) is a spool or reel 28 for a relatively narrow shield or breaker strip B which may be of glazed paper or the like, the spool being so located that said strip will be positioned crosswise of the platen 3 and overlie a margin of corresponding width along the lower edge of sheet S. A brake spring shown at 29 (Fig. 1) bearing against one side of the spool 28 yieldingly resists withdrawal of the strip B, which latter, as shown in Fig. 4, under-passes a guide pin 30 on the bracket arm 27 and which, after traversing the sheet S, passes beneath through a combined guide clamp jointly formed by the supplemental plate 25 and a member 31 overlying it, see Figs. 1, 2 and 4. The clamp member 31 has upstanding ears 32 (Fig. 4) which pivot on a transverse fulcrum pin 33 secured at its opposite ends in upright bearing projections 35 on the plate 22. A coiled spring 36 surrounds the pin 33 intermediate the ears 32, one end 37 of said spring being anchored on one of the bearing projections 35 while the other end 38 bears downward on the clamp member 31. As shown, the outer edge of the clamp member is beveled as at 31a for the purposes of a knife against which the breaker strip B may be torn. For convenience in initially threading the strip B in the machine, the clamp member 31 may be lifted by pressure upon an upwardly extending finger tab projection 39 thereon, such lifting movement being limited by engagement of said projection with a corresponding fixed finger tab projection 40 on the plate 25, see Figs. 1, 2, and 4.

Secured in the vertical axis bosses 5 and 7 of the base 1 are studs 41, 42, respectively, which are slidingly engaged by vertically spaced bosses 43, 43a and 44, 44a at the corners of a relatively narrow open rectangular cradle frame 45, which overlies the depressed portion 4 of the base 1, and which, by reason of its function presently explained, I will term a "carrier;" and surrounding the studs 41, 42 in the intervals between the bosses 43a and 44a and abutment washers or collars 46 and 47 supported on cross pins 48, 49 in said studs, are helical springs 50, 51. The front and rear cross rails 52, 53 of the carrier 45 are notched at suitably spaced intervals transversely as at 54 for reception and slidable guidance of printing bars such as shown at 55, the carrier being normally held at the level illustrated in Figs. 2-4 by the springs 50, 51 with the lower edges of said printing bars above the plane of the sheet S on the platen 3. As shown, the notches 54 are closed by cap bars 56 and 57 secured by screws to the tops of the cross rails 52, 53 on the carrier 45.

Positioned crosswise of the carrier 45 with the ends of its shaft 60 freely journalled in vertical slots 61 in the opposite side rails of said carrier, is an inking roll 62 which contacts with the bottom edges of the printing bars 55, and which is divided into sections for inks of contrasting colors. For example those sections of the roll 62 designated 62a may be for green ink, the sections 62b for blue ink, and the remaining narrower sections 62c for brown ink. Disposed forwardly alongside the inking roll 62 is an applicator roll 63 which is correspondingly divided into sections for the contrastingly colored inks. The shaft 65 of the applicator roll 63 has its ends engaged in journal slots 66 in the side members of the frame 45, said slots being inclined downwardly to urge the roll 75

into contact with the inking roll 62 as clearly shown in Figs. 2 and 3. In order that the applicator roll 63 may be retracted from the inking roll 62 when desired or required, I have provided 5 a lifting means consisting of a transverse rock shaft 66 which is journalled in the side rails of the frame 45; fingers 67 on said shaft for under-reaching the roll shaft 65 at its ends; a manipulating handle projection 68 at one end of the rock shaft; and a fixed keeper 69 with a notch 69a to cooperate with the handle projection 68 in holding the applicator roll in its retracted position, said keeper being secured to one end of the cap bar 56. From Figs. 1 and 2 it will be observed that the shaft 65 of the applicator roll 63 is fitted at one end with a hand crank 70, and immediately inward of said crank with a collar 71 having a circumferential cam groove 72 in engagement with a lateral angular stud projection 73 at the corresponding side of the frame 45. As a consequence of this construction, the applicator roll 63 is reciprocated endwise as it is rotated, with a result that the differently colored inks are uniformly applied to and distributed on the several sections of the roll 62. The inks may be fed to the applicator roll 63 in any convenient way, for example, from a sectional trough (not shown) placed therebeneath on the depressed portion 4 of the base 1. Mounted in spaced bearing brackets 75 (Figs. 1-3) at the front of the frame 45 is a transverse roller 76 which constitutes a moving support for the front ends of the printing bars 55.

At their front ends, the printing bars 55 are secured in a holder having the form of a cross head 77, which (see Fig. 5) is notched as at 78 like the cross bars 52, 53 of the carrier 45 to receive said bars, and which is provided with a cap bar 79 with a resilient frictional facing 79a at the bottom thereof, said bar being apertured to 40 clear studs 80 upstanding from the holder, and said studs being threaded for engagement by thumb clamp nuts 81. The holder 77 is secured at its opposite ends by means of jam nuts 82 to longitudinally extending supporting rods 83 which have sliding bearing in the cross bars 52, 53 of the carrier 45 adjacent the bottom of the latter and which pass through clearance openings 84 in the front and rear walls of the raised portion 2 of the machine base 1. Each of the rods 83 is fitted at its outer end with a grasp knob 85 to facilitate moving the holder 77 relative to the carrier 45, the inner limit of such movement being determined by engagement of a stop ridge 86 thereon with the front ends of the journal brackets 75 for the roller 76, see Figs. 2 and 3.

By reference to Figs. 1-3, it will be seen that the corner studs 42 and similar studs 87 upstanding from the bosses 6 extend well up from the base 1 to afford attachment for collars 88, 89 with lateral bosses 88a, 89a in which the ends of longitudinally extending horizontal rods 90 are fixedly secured. As shown, these rods 90 are engaged by sleeves 92, which together with a connecting cross bar 93, constitute a slide carriage for a transversely extending tubular eccentric auxiliary printing bar depressing element 95 with end trunnions 96 journalled in the sleeves 92 and with an upwardly projecting manipulating handle 97 at the center. As shown, the lower portion of the eccentric element 95 engages a rounded leaf spring 98 which is secured along one of its longitudinal edges to said cross bar 93.

Journalled in suitably spaced bearings 100 at the top of the cap bar 57 on the frame 45 is a rock shaft 101 which carries a plurality of rear-

wardly extending fingers 102 which are relied upon to hold the sheet S down on the platen 3. The shaft 101 is subject to the torsional action of a helical spring 103 (Figs. 1 and 4) by which the fingers 102 are yieldingly urged toward the platen 3. When desired or required the fingers 102 may be lifted through turning the shaft 101 against the action of the spring 103 by means of a manipulating handle 104 at one end thereof (Fig. 4). When desired, the fingers 102 may be locked in 10 raised position by turning the shaft 101 anti-clockwise in Fig. 3 and engaging the handle 68 in the notch 105a of a keeper 105 on the cap bar 57 of the carrier frame 45.

As a means for actuating the frame 45 to bring 15 the inner ends of the type bars 55 down into contact with the sheet S, I have provided a lever 106 in the form of a yoke with side arms 107 connected at their outer ends by a cross bar 108 which is adapted to be depressed by the fingers. 20 The inner ends of the arms 107 are pivoted at 109 to upstanding lugs 110 on the low portion 4 of the base 1, while at an intermediate point, said side arms have pivotal connections as at 111 with the sides of the frame 45.

The use and operation of the machine is as follows:

The printed form sheet S is first placed upon the platen 3 with its longitudinal rear edge abutting the depending ridge 17 of the gauge bar 16 as shown in Fig. 2, and advanced to the desired extent on the platen by manipulation of the finger knob 23 by which the feed rollers 21 are operated. The holder 17 is thereupon shifted 30 forwardly, i. e., upwardly in Fig. 1 from the retracted position indicated in dot-and-dash lines to the full line position in which latter position the printing bars 55 project over the platen 3. During this movement of the holder, the differently colored inks are applied to the bottom edges 35 of the printing bars 55 of corresponding groups by the inking roller 62, whereof the shaft 60 is free to revolve in the journal slots 61 of the carrier frame 45. The yoke lever 106 is next operated by pressing downwardly upon its cross bar 108 with the one hand to lower the carrier 45, as a result of which the forwardly projecting ends of the printing bars 55 are brought into 40 engagement with the sheet S. Then, in order to insure firmer contact of the printing bars 55 with the sheet S, the auxiliary pressure means, that is to say the eccentric member 95, is swung counter-clockwise in Figs. 2 and 3 by means of its handle 97 until the interposed spring element 98 bears firmly down upon said printing bars. In this connection it is to be noted that the 45 spring element 98 operates as a means to prevent shifting of the printing bars under the rolling action of the eccentric pressure member 95 as the latter is rotated. The carriage for the auxiliary pressure member 95 may, of course, be shifted along the bars 90 to any desired position 50 in accordance with the extent to which the printing bars 55 project beyond the carrier 45. With the inking roll 62 subdivided for color as shown in Fig. 1, thick vertical green lines will be printed in the subdivisions S¹ and S³ of the form sheet, thick vertical blue lines in the subdivisions S² and S⁴, and thick vertical (total) lines in all four of said sections during the first impression, the breaker strip B operating incidentally to shield the lower margin of the sheet below the horizontal line L—L in Fig. 6. The auxiliary pressure member 95 is thereupon swung back to 55 its normal position, the carrier 45 allowed to rise

under the influence of the springs 59, 51 so that the outer ends of the printing bars 55 clear the sheet S on the platen 3, and the holder 17 moved to retracted position. Selected printing bars 55 are thereupon properly adjusted in the holder 17 and the sheet S shifted on the platen so that upon the next printing operation carried out in the same manner as above explained, vertical blue lines are impressed for example in the sections S¹ and S² of the sheet S (Fig. 6). Before this is done, however, the clamp 31 is lifted and a clean length of the breaker strip drawn off, whereupon the clamp is again released to its normal position and the pulled length of said strip torn off against the knife edge of the clamp member. After the second impression, the holder is again retracted, selected printing bars 55 shifted as required and the sheet S moved laterally of the platen as may be necessary for application during the third impression, of vertical blue lines to the sections S² and S⁴ of the form sheet S. Occasionally it is incumbent upon the operator to rotate the applicator roll by means of its handle 10 for maintenance and distribution of an adequate supply of the contrasting inks upon the different sections of the inking roller 62.

I am not to be considered as restricted to the number of sections into which the inking roller 62 is subdivided in the example herein set forth for convenience of illustration, nor to the number of differently colored inks employed, since these considerations are variable within the scope of the appended claims. It is moreover to be understood that the printing bars 55 may be notched at their bottom edges to produce broken lines instead of solid lines; or, as another alternative, said bars may be provided at their bottom edges with type characters—all in accordance to the particular work for which the machine is intended to be used.

Having thus described my invention, I claim:

1. A printing machine comprising a platen for supporting a sheet which is to be printed; a plurality of printing bars; a holder in which the bars are arranged side by side and secured with capacity for being individually adjusted in the direction of their lengths to project to different extents beyond the holder and over the platen; a supporting carrier in which the bars are slideable endwise as a group; and means for moving the platen and the carrier relatively to effect contact between the printing bars and the sheet.

2. A printing machine according to claim 1, wherein the platen is flat and the printing bars are straight.

3. A printing machine according to claim 1, wherein the platen is flat and the bars are straight; and further comprising means for supporting a breaker strip of paper or the like crosswise over a portion of the platen below the printing bars and inward of the projected ends of the latter.

4. A printing machine comprising a platen for supporting a sheet which is to be printed; a plurality of printing bars; a holder in which the bars are arranged side by side and secured with capacity for being individually adjusted in the direction of their lengths to project to different extents beyond the holder; and a carrier by which the holder is sustained for movement of the printing bars endwise from a retracted position to an advanced position over the sheet on the platen, said carrier being movable perpendicularly of the platen for the purpose of bringing the bars into printing contact with the sheet

after the holder has been moved to advanced position as aforesaid.

5. A printing machine according to claim 4, further comprising means on the carrier for inking the type bars incident to movement of the holder toward and away from the platen.

6. In a printing machine, a base having a depressed portion at the front, and a raised portion at the rear with a flat horizontal surface serviceable as a platen for a sheet which is to be printed, and a horizontal carrier positioned over the depressed frontal portion of the base; a plurality of laterally spaced printing bars confined to endwise movement toward and away from the platen in the carrier; a holder in the form of a cross head positioned forwardly of the carrier in which the bars are secured at their outer ends with capacity for being individually adjusted in the direction of their lengths so that their inner ends may be projected to different extents beyond the holder; means whereby the holder is confined in the carrier with capacity for movement relative to the platen to bring the inner ends of the printing bars over the sheet on the platen; and means by which the carrier is sustained at a height such that the printing bars will normally be above the level of the platen during shifting of the holder, and which will yield to permit subsequent depression of the carrier to bring said bars into contact with the sheet

30

7. A printing machine according to claim 6, wherein the carrier has sliding engagement for up and down movement with a plurality of studs upstanding from the depressed portion of the base; and wherein helical springs surrounding the studs constitute the means for yieldingly sustaining the carrier.

8. A printing machine according to claim 6, further comprising an inking roller journaled at opposite ends on the carrier with its surface bearing against the bottom edges of the printing bars so as to apply ink to said bars as the holder is moved toward and away from the platen.

9. A printing machine according to claim 6, further comprising means for shifting the sheet on the platen in a direction laterally of the printing bars; an inking roller journaled at opposite ends on the carrier with its surface bearing against the bottom edges of the printing bars so

40

5. as to apply ink to said bars as the holder is moved toward and away from the platen, said roller being divided into sections for differently colored inks, the surfaces of which sections bear upon definite groups of the printing bars.

10. A printing machine according to claim 6, further comprising means for supporting a breaker strip of paper or the like crosswise of the platen below the printing bars and inward of the projected ends of the latter.

11. A printing machine according to claim 6, further comprising leverage means for actuating the carrier; auxiliary pressure means supported above the level of the printing bars; and means whereby the pressure means may be operated after the bars have been advanced over the platen and the carrier depressed to urge the printing bars into more positive contact with the sheet.

20

12. A printing machine according to claim 6, further comprising leverage means for actuating the carrier; auxiliary pressure means; means for supporting said auxiliary pressure means above the level of the printing bars with capacity for being shifted in the direction of the printing bars; and means whereby the pressure means may be operated after the bars have been advanced over the platen and the carrier depressed to urge the bars into firmer contact with the sheet.

25

13. A printing machine comprising a platen for supporting a sheet which is to be printed; a plurality of printing bars; a holder in which the bars are arranged side by side and secured with capacity for being individually adjusted in the direction of their lengths to project to different extents beyond the holder and over the platen; a yieldingly mounted carrier in which the bars are slidably endwise as a group; pressure means supported over the platen above the level of the printing bars; and means for operating the pressure means to press the bars into contact with the sheet.

30

14. A printing machine according to claim 13, wherein the pressure means includes a rotatable eccentrically-mounted member which extends transversely of the printing bars, and a yielding spring plate positioned between the eccentrically-mounted member and the printing bars.

MAURICE B. WILLIS.
